EDGE-GUIDE FOR BOOK-SEWING
MACHINES

Park A. Herr, Hillside, N. J., assignor to The
Singer Manufacturing Company, Elizabeth,
N. J., a corporation of New Jersey

Application August 22, 1931. Serial No. 558,757

5 Claims. (Cl. 112—21)

This invention relates to book-sewing machines of the straight-away long stitch-length type, such as disclosed in my copending application, Serial No. 558,756, filed herewith.

5 The invention has for an object to provide such a machine with an edge-guide having means to insure that the first and last stitches will be made within the book and at safe distances from the beginning and ending or leading and trailing edges of the book.

With the above and other objects in view, as will hereinafter appear, the invention comprises the devices, combinations and arrangements of parts hereinafter described and claimed.

15 The features of the invention and the advantages attained thereby will be readily understood by those skilled in the art from the following detailed description of a preferred embodiment of the invention illustrated in the accompanying drawing, of which Fig. 1 is a left end elevation of a book-sewing machine and edge-guide embodying the invention. Fig. 2 is a plan view of the edge-guide in working position on the bed of the machine, as shown in Fig. 1. Fig. 3 is a 25 section on the line 3—3, Fig. 2, and Fig. 4 is a perspective view of the edge-guide.

The sewing machine to which the edge-guide is shown attached, is constructed substantially in accordance with the disclosure of my said copending application. It comprises a bed 1 and needle-bar head 2 in which are journaled the reciprocating needle-bar 3 and reciprocating rotary awl-bar 4 carrying, respectively, the needle 5 and awl 6. The needle passes through the needle-hole 35 5' in the presser-foot 7 and through the usual throat-plate 8 for cooperation with the usual shuttle 9. The book is fed to the awl and needle in long stitch-lengths preferably by means of a four-motion feed-dog 10 in cooperation with 40 the upper walking foot 11; the work being held firmly on the throat-plate 8 by the presser-foot 7 during the return motion of the feed-dog 10 and walking foot 11. This walking foot and presser mechanism operates in the manner disclosed in my said copending application and further description thereof is believed to be unnecessary to an understanding of the present invention. It will suffice to explain that in the simultaneous descent of the awl and needle-bars, 45

50 the awl 6 makes a hole in the book b. After the awl and needle rise clear of the book, the latter fed a stitch-length to carry the hole just formed to the needle 5 which, on the next descent of the awl and needle-bars, stitches through the hole 55 formed by the previous descent of the awl; the awl

being disposed a stitch-length in advance of the needle.

The edge-guide 12 is provided primarily to insure a uniform spacing of the line of stitches 13 from the edge of the book b. The edge-guide comprises a base 14 including slotted attaching feet 15 which are screwed to the bed 1. The guide 12 is formed with a vertical guide-face 16 the forwardly disposed portion of which is provided with a series of screw-holes 17, any selected one of which may receive the screw 18 passing through the slot 19 in the angle-piece 20, the face 21 of which constitutes a stop against which one end of the book b is placed at the beginning of a sewing operation to insure that the first hole formed in the book by the awl 6 will not be at or too near the leading edge b' of the book.

It is also important that the book be so positioned at starting, that the last stitch will not be taken at or too near the trailing edge b'' of the book. To enable the operator to guard against misplacement of the last stitch, the top edge of the guide-bar 12 is graduated with a series of marks or notches 22 spaced a stitch-length apart; the initial graduation mark 22' being spaced from the path of the awl 6 one or more whole stitch-lengths. These graduations 22 indicate in advance of a sewing operation the points where the stitches will be made in the book. Hence, by taking care that the book is not started with its trailing edge b'' too near one of the marks 22, the operator insures that the last stitch will be made at a safe distance within the edge b''. Where several books of the same size are to be stitched in succession, the stop 20 may be adjusted with its face in the desired starting position intermediate the marks 22. The operator preferably starts the book so that the leading edge b' overlaps the awl path the same distance d that the trailing edge b'' lies in advance of one of the graduation marks 22, as shown in Fig. 2. This distance can always be adjusted to be equal to or greater than half a stitch-length, regardless of the exact length of the book.

100 The bar 12 is preferably provided with cut-outs or notches 23 to facilitate the blowing away by the air-nozzle 24 of paper chips removed from the book by the awl 6.

Having thus set forth the nature of the invention, what I claim herein is:—

1. In a book-sewing machine, the combination with stitch-forming mechanism including a reciprocating needle, and feeding mechanism, of an edge-guide disposed alongside the line of

seam-formation and graduated in stitch-lengths in advance of the needle.

- 5 2. In a book-sewing machine, the combination with stitch-forming mechanism including a reciprocating needle, feeding mechanism, and an awl disposed a stitch-length in advance of said needle, of an edge-guide disposed alongside the line of seam-formation and graduated to indicate stitch-lengths in advance of said awl.
- 10 3. In a book-sewing machine, in combination, stitch-forming mechanism including a reciprocating needle, and straightaway feeding mechanism, said stitch-forming and feeding mechanisms being adapted to sew a line of long book-fastening stitches, and means in advance of said stitch-forming mechanism graduated to indicate whole stitch-lengths in advance of said needle.

4. In a book-sewing machine, in combination, stitch-forming mechanism including a reciprocating needle, straightaway feeding mechanism, an awl disposed a stitch-length in advance of said needle, and means for indicating at the 80 time the first hole is formed in a book of any length within predetermined limits the point adjacent the trailing edge of the book where the last hole will be formed.

5. In a book-sewing machine, in combination, 85 stitch-forming mechanism including a reciprocating needle, straightaway feeding mechanism, an awl disposed a stitch-length in advance of said needle, and means for indicating in advance of a sewing operation the point adjacent the 90 trailing edge of a book of any length within given limits where the last stitch will be formed.
